Primary Examiner — Keli L Hill*Assistant Examiner* — Sara S Sahneh(74) *Attorney, Agent, or Firm* — Burr & Forman, LLP(57) **CLAIM**

The ornamental design for a torque wrench, as shown and described.

DESCRIPTION

FIG. 1 is a perspective view of a torque wrench of the present invention;

FIG. 2 is a front view of the torque wrench of FIG. 22;

FIG. 3 is a back view of the torque wrench of FIG. 22;

FIG. 4 is a right side view of the torque wrench of FIG. 22;

FIG. 5 is a left side view of the torque wrench of FIG. 22;

FIG. 6 is a top view of the torque wrench of FIGS. 22; and,

FIG. 7 is a bottom view of the torque wrench of FIG. 22.

The broken lines of FIGS. 1–7 form no part of the claimed design.

1 Claim, 4 Drawing Sheets(56)
